VALVE AND BURNER CONSTRUCTION

Roman F. Drezdon, Milwaukee, Wis.

Application September 11, 1933, Serial No. 688,878

16 Claims. (Cl. 158—115)

This invention relates to a valve and burner construction.

Objects of this invention are to provide a multiple burner construction in which there is a center burner, a succeeding burner, and an outer burner, so constructed that the center burner may operate alone or the center and intermediate burner, or all three burners may operate jointly.

Further objects are to provide a multiple burner construction which is so made that it cannot be extinguished by a transverse current of air as means are provided for maintaining a small light which will re-ignite the main burner when the draft is stopped, and which also cannot be extinguished by the overflowing of a vessel on to the burner, as, for example, when a vessel boils over.

Further objects are to provide a burner construction in which a plurality of units constitute the burner, and in which a plurality of burners may be arranged in any desired relative position, for example, as that usually found on the tops of gas stoves, and in which pilot light means are provided for each burner, a single pilot light flame for its individual burner being automatically controlled by the valve for such burner, so that the pilot light is lighted whenever the burner is turned on and the flame projected towards the burner, and thereafter in which the pilot light is extinguished when the main burner valve is turned to a full on position preceding the reverse rotation of the valve.

A particularly important object of this invention is to provide a multiple burner construction in which all of the burner sections, large, medium and small, may be turned down or simmered down at once so that a uniform heating over the entire area of the multiple burner is provided, as, for example, when it is desired to heat a relatively wide bottom vessel or utensil.

Thereafter all three sections can be turned on in full force, or, if it is desired to turn down all three sections at once, it is done by turning the main movable member towards the off position. When a smaller area of the burner is desired, it may be accomplished by turning the main movable member further to the off position. Then the outermost section is turned off completely and the medium and small sections slowly increase to a full flame. Said medium and small sections can also be turned down or simmered simultaneously. By further turning the main movable member to the off position, the medium section is turned off completely and the

small section slowly increases to a full flame and can also be turned down or simmered to a minimum. All these results are obtained by means of a single valve.

Further objects are to provide a valve construction for a multiple section burner which is so made that seating of the valve is insured, and which is provided with a plug or other member relatively movable with respect to the main movable valve body and held in engaging position by means of a spring or similar member, such last member controlling the pilot light in an automatic manner, and also to provide means associated with the valve which insures a click when the successive burners are turned on and when at least two of the burners are turned off.

Further objects are to provide a construction which is easy to manufacture and assemble, which is inexpensive, and which has a relatively small number of parts.

An embodiment of the invention is shown in the accompanying drawings, in which:

Figure 1 is a plan view, partly broken away, showing the top of a gas stove with the burners in place and with the grating of the stove removed.

Figure 2 is a horizontal sectional view through the valve body portion with the valve plug and associated parts partly in section and with the mixing chambers or tubes of the burners partly in section.

Figure 3 is a sectional view on the line 3—3 of Figure 2.

Figure 4 is a sectional view on the line 4—4 of Figure 2.

Figure 5 is a sectional view on the line 5—5 of Figure 2.

Figure 6 is a view of the inner end of the valve.

Figure 7 is a sectional view on the line 7—7 of Figure 2.

Figure 8 is a sectional view on the line 8—8 of Figure 2.

Figure 9 is a sectional view on the line 9—9 of Figure 8.

Figure 10 is a sectional view on the line 10—10 of Figure 11.

Figure 11 is a sectional view through the pilot light, such view being taken on the line 11—11 of Figure 10.

Figure 12 is a sectional view on the line 12—12 of Figure 11.

Figure 13 is a sectional view on the line 13—13 of Figure 1.

Figure 14 is a sectional view on the line 14—14 of Figure 13.

Referring to the drawings, it will be seen that a gas stove has been indicated generally by the reference character 1 and the supply main or supply pipe by the reference character 2. A plurality of burners are positioned in any suitable arrangement, for instance, in the spaced arrangement indicated in Figure 1. Each burner is a multiple section burner and consists of a central burner section 3, an intermediate burner section 4, and 10 an outer burner section 5. These burner sections are joined in an integral manner by webs, as shown in Figure 1, and are preferably spaced apart to provide a free air supply between the burners. These burner sections are supplied respectively through the supply pipes or mixture tubes 6, 7 and 8, respectively. The burner tubes or passageways are formed in a single manifold indicated generally by the reference character 9. Obviously these manifolds may be made of any 15 length desired to accommodate the particular positioning of the burner, as indicated in Figure 1, and it is intended that the mixing tubes or chambers 6, 7 and 8 be arranged in the horizontal plane as indicated particularly in Figures 1 and 2.

25 A pilot light is provided and is indicated generally by the reference character 10. This pilot light is provided with a casing 11 which is equipped with holes 12 directed towards the respective burners and located in its side walls. It 30 is also provided with upper ventilating holes 13 and with lower air inlet holes 14.

The pilot light comprises a conical body portion 15 which is provided with a central aperture or passageway 16 to which a constant supply of gas is furnished by means of the pipe 17 which, as may be seen from Figure 1, is directly connected to the supply main 2 or supply manifold and is controlled by a permanently adjusted valve 18.

40 In addition to the central aperture 16 the pilot light is provided with four inwardly and upwardly slanting passageways 19, see Figure 11, which are connected to the supply pipes 20 hereinafter described. Each of these upwardly extending passageways 19 is provided with a lateral outlet 21 in line with the appropriate opening 12 and pointing toward its corresponding burner. In other words, where four burners are used, four openings 21 are provided and four independent supply pipes 50 20 are furnished.

The central aperture 16 is provided with transverse branch apertures 22 which open outwardly at points intermediate the apertures 21 so that the constantly burning small flames from the apertures 22 will ignite any one of the gas streams which may pass from the apertures 21 in a manner hereinafter to appear.

Referring to Figures 2, 8 and 9, it will be seen that each burner is supplied with a gas nozzle 23 which opens into a vertically enlarged chamber 24. This chamber communicates with the appropriate passageway 6, 7 or 8 and is closed by means of a plate 25, see Figure 9, provided with an aperture 26 which may be more or less closed 60 by an adjustable, slidable plate 27, such plate being locked in adjusted position by means of a screw 28 passing through a slot in the plate.

The nozzles are carried by the three gas supply pipes 29, 30 and 31, as most clearly shown in Figure 2. The smallest aperture nozzle is carried by the pipe 29, the medium, by the pipe 30, and the largest, by the pipe 31. The mixing tubes 6, 7 and 8 are also of successively increasing size. The 75 gas supply pipes 29, 30 and 31 are integrally

formed with the body portion or main casing 32 of the valve.

The valve comprises the casing 32, the body portion of which is equipped with three main ports 33, 34 and 35 communicating respectively with the pipes 29, 30 and 31, see Figures 3 and 4. It is also provided with a port 36 which is preferably formed in a threaded projecting member 37, see Figures 1 and 2, which in turn is connected with its appropriate supply pipe 20 leading to the pilot light and communicating with the aperture 21, see Figure 11, which is directed towards the burner having the valve under consideration.

The casing 32 is also provided with a port 38 formed in a threaded projecting portion 39 and 15 screwed into the supply main 2, as shown most clearly in Figure 3. The casing is provided with shoulders or stops 40, see Figure 2, which cooperate with a pin 41 carried by the movable portion 42 of the valve to limit the valve in its two 20 extreme positions. Preferably a cap 43 is screwed upon the projecting end of the casing 32 or body portion of the valve and is provided with a spring 44 bearing against the movable member 42 of the valve. Obviously the movable member 42 25 could be made in other shapes than that described, but in the form shown it is of a conical contour and the casing 32 or body portion is correspondingly bored out. The valve stem 45 is rigid with the valve and is provided with a ma- 30 nipulating handle 46.

The movable member 42 or plug of the valve is provided with a central aperture 47 which terminates in a conically bored portion within which latter a conical plug or auxiliary movable 35 member or valve 48 is fitted. This member 48 is held in place by means of a spring 49 which bears against a plate 50 at one end and which bears at the other end against a cap 51 slidably fitting within a sleeve 52 forming an integral extension 40 of the member 48. The plate 50, as may be seen from Figure 7, is provided with a central rounded portion 53 and with a projecting notched portion 54 which latter fits over a projecting arm 55, such arm having an inwardly extending por- 45 tion bearing against the cap 51, as may be seen from Figure 2. The portion 53 is joined to the portion 50 by means of a neck 50'. Thus it will be seen that the member 48 is spring pressed into gas-tight engagement with the member 42 and 50 is movable relative to the movable member 42.

The plate 50 is provided with an aperture 56, see Figure 7, and the end of the member 42 is provided with a wedge-shaped or cam-shaped nib or projection 57. This projection is provided to 55 cause a click in cooperation with the plate 50 as the valve is turned. Upon the opening motion of the valve, which is a counterclockwise direction as viewed in Figure 7, the first click occurs when the projection 57 strikes the plate 50 and raises 60 it. This corresponds to the opening of the central burner supply. The next click occurs when the projection 57 snaps into the aperture 56, which corresponds to the subsequent opening of the gas supply to the intermediate burner sec- 65 tion. The third click occurs when the projection 57 passes from beneath the plate 50, which corresponds to the subsequent opening of the fuel supply for the outermost burner. Upon closing there are three distinct clicks in the reverse 70 manner to that described, as is apparent from an examination of Figure 7 in conjunction with Figure 2.

The member 48 is provided with a port or aperture 58 which registers with a corresponding port 75

or aperture 59 in the member 42, as most clearly shown in Figure 5. The member 42 is provided with an annular channel 60 in permanent communication with the port 59 and which, when the member 42 is turned, communicates with the pilot outlet port 36.

The main movable member 42 of the valve is also provided with an annular tapering port or aperture 61, see Figures 2 and 3. This aperture 61 communicates with the inlet aperture or port 38 as the valve is opened, that is to say, as it is turned in a counterclockwise direction, as viewed in Figure 3. Thus the supply port 38 is placed in communication with the central aperture 47 of the main member 42.

The annular tapering port or aperture 61 is located so that the narrow end of the aperture 61 is in communication with the aperture 38 when gas is fed to the innermost burner section 3, and the widest part of the aperture 61 is in communication with the aperture 38 when gas is fed to all three sections of burner 3, 4 and 5.

Thus it is easily understood that the annular tapering port or aperture 61 serves as a regulator for the amount of gas required for the various sizes of the multiple burner sections. For instance, when all three sections of the multiple burner are turned on in full force, the largest amount of gas is required for a sufficient supply to all three sections. At this time the widest part of the aperture 61 is in communication with the aperture 38, and when the intermediate and innermost sections 4 and 3 are turned on in full force, then the center part of the aperture 61 is in communication with the aperture 38, and when the innermost section 3 is turned on in full force, then the narrowest part of said annular tapering port or aperture 61 is in communication with the aperture 38.

It is easily understood that the manner of forming the aperture 61 causes such aperture to serve as a regulator of gas to all three multiple burner sections 3, 4 and 5.

The main member 42 is further provided with a plurality of radial apertures or ports 62, 63 and 64, as shown in Figures 2 and 4. It is to be noted from Figure 2 that a small flattened portion is formed on the plug member adjacent the outer side of each of the apertures 62, 63 and 64.

As the valve is turned on, that is, in a counterclockwise direction, as viewed in Figure 4, the aperture 62 first registers with the aperture 35 and the innermost burner is thus supplied with fuel. Further turning of the valve causes the aperture 63 to register with the aperture 35 and the aperture 62 to register with the aperture 34. Still further turning of the valve causes the aperture 64 to register with the aperture 35 and the apertures 62 and 63 to register respectively with the apertures 33 and 34.

However, the apertures 62, 63 and 64 upon reverse rotation, that is, closing motion of the valve in a clockwise direction, as viewed in Figure 4, cause first a simultaneous decrease in the fuel supply to all of the burner sections, without, however, completely extinguishing any burner due to the fact that there is a slight overlap between the movable and the stationary apertures or ports, and also due to the slight flattening of the plug adjacent the outer portions of the apertures 62, 63 and 64, as indicated at 63' in Figure 2.

However, after the aperture 62 has left the aperture or port 33, the outermost burner is extinguished and the apertures 63 and 62 gradually

register fully with the apertures 34 and 35, and consequently the flames of the intermediate burners gradually rise to full height.

Upon further closing motion of the valve, the apertures 63 and 62 gradually move from the ports 34 and 35, thus decreasing the fuel supply to the intermediate and innermost burner, thus causing them to simmer down. Subsequently the intermediate burner is extinguished and the central or innermost burner again is gradually provided with full fuel supply. This burner may be dimmed by further closing motion of the valve and may be finally extinguished when the valve is completely closed.

The operation of the valve is as follows: Assuming that the valve is in its cut off position, as shown in Figures 2 to 7, and assuming that the valve is turned in a counterclockwise direction, as viewed in Figures 3 to 7 (the opening movement), it is apparent that gas is admitted to the central chamber 47 of the valve at the early portion of this motion. In addition gas is admitted to the pilot light port 36. The pilot light for this particular burner is thus projected towards the burner. Continued motion of the valve admits gas first to the port 35, at which time the central burner will be lighted. Upon further motion, the next burner is lighted, and upon completion of the motion the final or outer burner is lighted.

In addition to this, the sleeve 52, see Figures 2 and 7, which is approximately semi-circular, strikes the projecting neck 55 and rotates the movable member or auxiliary valve 48 with reference to the main valve 42, thus cutting off communication between the ports 58 and 59, see Figure 5. This extinguishes the pilot light for that particular burner. The steady pilot light furnished by the pipe 17 of course burns continuously.

If only one burner is desired, the valve is rotated in a clockwise direction, as viewed in Figures 3 to 7, until only the central burner is supplied with gas, as will be apparent from the previous description and from these figures. If two burners are desired, it is obvious that this may be readily secured, or if all three burners are desired, this also may be readily obtained. It is to be noted, however, that all of the burners may be simultaneously simmered down, as, for instance, when a relatively wide utensil is placed over the burner and only a moderate uniformly distributed heat is desired.

After the outermost burner is cut off, it is obvious that the flames of the intermediate and main burner will begin to rise gradually to a full flame and these may then be simmered down. Similarly the intermediate burner may be cut off and the central burner flame will gradually begin to rise to full force and then may be simmered down and finally cut off. During the completion of the closing motion of the valve, the movable member or auxiliary valve 48 is rotated back to its initial position, as viewed in Figure 5, as the sleeve 52 then engages the arm 55 and the valve is thus ready for a subsequent opening motion.

It is apparent that any number of these composite or multi-section burners can be employed and arranged in any desired position, such, for instance, as shown in Figure 1, and that the individual pilot light tubes 20 will be run one from each valve to its appropriate portion of the pilot light as previously described.

Means are provided for preventing the com-

plete extinguishing of the burner from a cross-draft, for example, or from the boiling over of liquid and the temporary flooding of the burner. These means are very easily provided by forming 5 what is in effect a small Bunsen burner consisting of a channel-shaped plate 65 secured by means of a screw or other member 66 to an upwardly projecting portion 67 integral with the innermost burner and provided with an outwardly directed 10 discharge orifice 68 in line with the horizontally projecting portion of the channel-shaped plate 65.

This channel-shaped plate extends downwardly as indicated at 65' in Figure 13, preferably into 15 the central opening 69 of the innermost burner so that it secures a fresh air supply, such air passing around the sides of the projection 67, as is obvious from Figure 14. It is apparent, therefore, that a cross-blast of air, though it 20 might blow out the flames from the burners, nevertheless will not blow out the shielded flame beneath the plate 65 and from the orifice 68. Consequently when this blast of air ceases, or 25 when the flooding of the burner ceases, due to the overflow previously mentioned, the burner will be re-ignited in an automatic manner.

It is to be noted from Figures 1 and 13, that a series of small holes 65'' are formed in the burner section and are arranged in line with the aperture 68 (Figure 13) so that the flame is carried 30 from burner section to burner section.

It is to be noted from Figure 13 that the burners may be provided with outlet apertures either vertically or at an angle as desired.

35 It will be seen that a very economical form of multiple burner and associated valve has been provided by means of which one or more burners may be automatically lighted from a single control valve and may be turned on either successively or simultaneously. Thus it is apparent that all of the burners may be operated at full 40 output or else may be simultaneously simmered down, and that subsequently the intermediate and inner burner will gradually come up to full output when the outermost burner is cut off. Correspondingly, the intermediate and inner burner 45 may be simmered down, the inner burner gradually coming up to full output when the intermediate burner is cut off. Finally, the inner burner may be simmered down or may be completely cut off.

It will be seen further that the auxiliary valve, or auxiliary movable member with reference to the main movable member, is automatically positioned by the operation of the main valve or 55 main member without any thought on the part of the operator so as to properly control the pilot light.

It will be seen further that the entire device 60 is of simple and sturdy construction and may be easily and cheaply made and installed.

Although this invention has been described in considerable detail, it is to be understood that such description is intended as illustrative rather 65 than limiting, as the invention may be variously embodied and is to be interpreted as claimed.

I claim:

1. A burner comprising a plurality of burner sections, a valve comprising a body portion having a main inlet and a separate outlet for each burner section and a pilot outlet, a pilot light connected to said pilot outlet, movable valve means for controlling said outlets, said valve means including movable pilot control means directly controlling said pilot outlet, and means for

moving said movable pilot control means at full valve open position to close said pilot outlet and for moving said movable pilot control means at valve closing position to open said pilot outlet.

2. A burner comprising a plurality of burner sections, a valve comprising a body portion having an inlet and a separate outlet for each burner section and a pilot outlet, a pilot light connected to said pilot outlet, said valve having a main movable member controlling said outlets, and an auxiliary member automatically movable with respect to said main movable member and additionally controlling said pilot outlet, said auxiliary member directly cooperating with said main movable member. 15

3. A burner comprising a plurality of burner sections, a valve comprising a body portion having an inlet and a separate outlet for each burner section and a pilot outlet, a pilot light connected to said pilot outlet, said valve having a main movable member controlling said outlets, and an auxiliary member automatically movable with respect to said main movable member and carried by said movable member and additionally controlling said pilot outlet. 20

4. A valve for a burner having multiple burner sections, said valve comprising a body portion having an inlet and a plurality of outlets for respective connection to said burner sections, said body portion having a pilot outlet, a main movable valve member carried by said body portion and controlling all of said outlets, an auxiliary automatically movable member carried by said main movable member for additionally controlling said pilot outlet, and yielding means for holding said auxiliary member in contact with said main movable member. 25

5. A valve for a burner having multiple burner sections, said valve comprising a body portion having an inlet and a plurality of outlets for respective connection to said burner sections, said body portion having a pilot outlet, a main movable valve member carried by said body portion and controlling all of said outlets, an auxiliary automatically movable member carried by said main movable member for additionally controlling said pilot outlet, yielding means for holding said auxiliary member in contact with said main movable member, and stationary means carried by the body portion of said valve for controlling said auxiliary movable member. 40

6. In a burner construction the combination of a burner having a plurality of burner sections, a valve having a body portion provided with a separate outlet for each burner section and having a pilot outlet, a movable main valve member controlling said outlets, an auxiliary valve member automatically movable with respect to said movable member for additionally controlling said pilot outlet, a pilot having a constantly burning portion and having an opening directed towards said burner and connected to said pilot outlet, and means for supplying the constantly burning portion of said pilot with fuel independently of said valve. 55

7. In a burner construction, a main multiple section burner having an inner burner, an intermediate burner and an outer burner, mixing tubes forming a portion of said burner and projecting therefrom and supplying the several sections of said burner, a pilot light having a constantly burning portion, means for supplying fuel to said constantly burning portion, said pilot light having an aperture directed towards said burner, a valve having a plurality of outlets connected 60

to said mixing tubes and having a pilot outlet connected with said aperture of said pilot, a movable valve member carried by said body portion and having a hollow interior provided with outlet apertures adapted to align with the outlets in said body portion, and having an inlet aperture, said body portion having a main inlet adapted to align with the inlet aperture of said movable main valve member, and an auxiliary member movably carried by said main movable member for controlling the flow of fuel to the pilot outlet, said auxiliary member being automatically operated by the movement of said first mentioned valve member.

8. In a burner construction, a main multiple section burner having an inner burner, an intermediate burner and an outer burner, said burners being spaced apart by annular air passages, mixing tubes forming a portion of said burner and projecting therefrom and supplying the several sections of said burner, a pilot light having a constantly burning portion, means for supplying fuel to said constantly burning portion, said pilot light having an aperture directed towards said burner, a valve having a plurality of outlets connected to said mixing tubes and having a pilot outlet connected with said aperture of said pilot, a movable main valve member carried by said body portion and having a hollow interior provided with outlet apertures adapted to align with the outlets in said body portion, and having an inlet aperture, said body portion having a main inlet adapted to align with the inlet aperture of said movable main valve member, and an auxiliary member movably carried within said main movable member for controlling the flow of fuel to the pilot outlet.

9. A gas burner construction comprising a burner section, a pilot light having a constantly burning flame and having a port directed towards said burner section, and a valve controlling the supply of gas to said burner section, said valve having pilot light controlling means for supplying gas to the said port of the pilot light to project a flame towards said burner section from said pilot light when said valve is opening, said means turning on the supply of gas to said port from the initial opening movement of said valve and cutting off the supply of gas to the said port when said valve completes its opening movement, said pilot remaining on during the full opening movement of said valve.

10. A gas burner construction comprising a burner section, a pilot light having a constantly burning flame and having a port directed towards said burner section, and a valve controlling the supply of gas to said burner section, said valve having pilot light controlling means for supplying gas to the said port of the pilot light to project a flame towards said burner section from said pilot light when said valve is opening and from the initial opening movement of said valve, said means cutting off the supply of gas to the said port when said valve completes its opening movement and remaining in the cut-off position during closing motion of said valve.

11. A gas burner construction comprising a burner section, a pilot light having a constantly burning flame and having a port directed towards said burner section, and a valve controlling the supply of gas to said burner section, said valve having pilot light controlling means for supplying gas to the said port of the pilot light to project a flame towards said burner section from said pilot light when said valve is opening and from the

initial opening movement of said valve, said means cutting off the supply of gas to the said port when said valve completes its opening movement and remaining in the cut-off position during closing motion of said valve, said means being reset at the completion of the closing motion of said valve.

12. A gas burner construction comprising a burner section, a pilot light having a constantly burning flame and having a port directed towards said burner section, and a valve controlling the supply of gas to said burner section, said valve having pilot light controlling means for supplying gas to the said port of the pilot light to project a flame towards said burner section from said pilot light when said valve is opening and from the initial opening movement of said valve, said means cutting off the supply of gas to the said port when said valve completes its opening movement and remaining in the cut-off position during closing motion of said valve, said means being reset at the completion of the closing motion of said valve, said valve cutting off the supply of gas to said means when said valve is completely closed.

13. A burner construction comprising a plurality of burner sections, a valve having a body portion provided with a main inlet and an outlet to each burner section and a pilot outlet, movable valve means for controlling said outlets, a pilot light supplied from said pilot outlet, said pilot light projecting a flame to said burner sections until all sections are turned on, said valve means including a main movable member and an auxiliary member movable with respect to said main member, said auxiliary member additionally controlling said pilot light, and a stop for moving said auxiliary member to cut off said pilot light when said main movable member is turned to the limit of its opening movement.

14. A burner construction comprising a plurality of burner sections, a pilot light for said burner, a valve comprising a body portion having an inlet port and an outlet port for each burner section and a port for said pilot light, movable valve means controlling said ports, said movable valve means opening the pilot light port during the opening motion of said valve means and cutting off the pilot light at the completion of the opening motion of said valve means, said valve means having a plurality of regularly spaced apertures adapted to align with said outlet ports to said burner sections when said movable valve means is in fully open position, and adapted to successively gradually align with one less of said outlet ports as said movable valve means is turned towards closing position and simultaneously restricting the remaining ports, whereby all or any number of said burner sections may be simultaneously simmered down or turned on full or completely cut off by said valve means.

15. A burner construction comprising a plurality of burner sections, a pilot light for said burner, a valve comprising a body portion having an inlet port and an outlet port for each burner section and a port for said pilot light, movable valve means controlling said ports, said movable valve means opening the pilot light port during the opening motion of said valve means and cutting off the pilot light at the completion of the opening motion of said valve means, said valve means having a plurality of regularly spaced apertures adapted to align with said outlet ports to said burner sections when said movable valve means is in fully open position, and adapted to successively gradually align with one less of said

5 outlet ports as said movable valve means is turned towards closing position and simultaneously restricting the remaining ports, whereby all or any number of said burner sections may be simultaneously 5 simmered down or turned on full or completely cut off by said valve means, said movable valve means being axially flattened adjacent said apertures to compensate for wear.

10 16. A burner construction comprising a plurality of burner sections, a pilot light for said burner, a valve comprising a body portion having an inlet port, and an outlet port for each burner section, movable valve means controlling said ports, said valve means having a plurality of regularly spaced apertures adapted to align with

said outlet ports to said burner sections when said movable valve means is in fully open position, and adapted to successively gradually align with one less of said outlet ports as said movable valve means is turned towards closing position 5 and simultaneously restricting the remaining ports, whereby all or any number of said burner sections may be simultaneously simmered down, or turned on full, or completely cut off by said valve means, said movable valve means being provided with means for maintaining the internal gas pressure within said valve approximately uniform, irrespective of the number of sections of the burner turned on by the valve.

ROMAN F. DREZDON. 15
